UNITED STATES PATENT OFFICE.

WILLIAM H. KENDALL, OF BROOKLYN, NEW YORK.

ATTACHMENT FOR HOLDING STOCK WHILE PRESSING HATS.

SPECIFICATION forming part of Letters Patent No. 715,084, dated December 2, 1902.

Application filed July 9, 1902. Serial No. 114,952. (No model.)

To all whom it may concern:

Be it known that I, WILLIAM H. KENDALL, a citizen of the United States, residing in Brooklyn borough, New York city, in the 5 county of Kings and State of New York, have invented new and useful Improvements in Attachments for Holding Stock While Pressing Hats, of which the following is a specification.

By means of this invention stock can be 10 saved, as a comparatively small or reduced spare or waste supply of stock is required for securing a hold. The work being expedited or facilitated and the invention being adaptable to any shape of die or hat, the invention 15 has been found to be practical.

This invention is set forth in the following specification and claims and illustrated in the annexed drawings, in which—

Figure 1 is a front elevation, partly in section, of a hat-pressing device with the attachment, or rather two attachments, embodying this invention. Fig. 2 is a face view of the holding attachment or clamp in section along αx , Fig. 1. Fig. 3 is a plan view of part of 25 Fig. 1.

The operation of an upper die a and lower die b in pressing hats is familiar and need not be explained at length. When the stock to be pressed is held stretched between the dies 30 as they come together, operatives have to take hold at the front and back, as also at the sides, of the stock to hold the same stretched as required. Considerable space or waste stock has to be provided for such handhold, and 35 the spare being afterward cut or trimmed off is lost or wasted. By having a suitable attachment or gripping devices for holding, say, the sides of the stock, while leaving only the front and back thereof to be gripped by hand, 40 such waste can be materially reduced.

In the drawings is shown a stock-holding jaw or portion c , which can be actuated by lever or cam d to be moved from or locked to the die b , or rather into a channel or dent in 45 the die for enabling the jaw to secure a satisfactory grip. The jaw c is slidable on an upright e , or rather on a pivot or fulcrum f , carried by the upright. Lever d is practically made to fulcrum on this pivot. The lever is

shown as a cam, the high part of which pressing the jaw to the stock or die and moving somewhat beyond the dead-center locks the clamp or jaw in position for a required period. The jaw part c has of course suitable shoulders or engaging portions for the lever-cam 55 to take hold and reciprocate the jaw. The pivot f is suitably secured to the upright. A slot-and-bolt connection is practical, since when the bolt g is loosened the pivot, and with it the jaw and lever, is adjustable along 60 the slot. The upright is shown adjustable on a foot h . A nut-and-bolt connection, applied as shown at i , will enable the upright to be adjusted up or down or laterally—that is, 65 swung on bolt i as on a pivot and then secured at a slant. Accommodation for securing a clamping or holding action on a die or die portion not exactly level is thus provided. The foot h can be adjustably connected to the bed-plate, say by a bolt-and-slot connection. 70 The foot, with its various portions, being set as required can then be fastened by such bolt h .

In stating that the device of this invention is applied at the sides it is of course manifest that no limitation of the invention is implied, 75 as the device could also be applied or attached front and back and the sides of the stock pulled out by hand. This is, however, not considered so practical, as ordinarily a man can utilize his strength to better advantage 80 by pulling toward himself.

What I claim as new, and desire to secure by Letters Patent, is—

1. A stock-holding attachment or clamp comprising an upright, a pivot or fulcrum portion carried by the upright, a lever fulcrumed on said pivot portion and a clamping portion actuated by the lever. 85

2. A stock-holding attachment or clamp comprising an upright, a pivot or fulcrum portion carried by the upright, a lever fulcrumed on said pivot portion and a clamping portion actuated by the lever, said upright being slotted and said pivot being slidable or adjustable along the slot. 90

3. A stock-holding attachment comprising a clamping portion and lever, an upright or support on which the clamping portion and 95

lever are adjustably mounted, and an adjustable foot on which the upright is adjustably mounted.

4. A stock-holding attachment comprising
5 a clamping portion and lever, and an upright
for supporting the same and made vertically
and laterally adjustable.

In testimony whereof I have hereunto set
my hand in the presence of two subscribing
witnesses.

WILLIAM H. KENDALL.
